(57) **CLAIM**

The or design for a chair base, as shown and described.

DESCRIPTION

FIG. 1 is a perspective view showing the front, top and opposite sides of a chair base which forms my new design; FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and,

FIG. 7 is a right side elevational view thereof.

The broken lines in the figures depict portions of the chair base that form no part of the claim.
